UNITED STATES PATENT OFFICE.

IVAN D. THORNBURGH, OF OAKLAND, CALIFORNIA, ASSIGNOR TO AMERICAN CAN COMPANY, OF SAN FRANCISCO, CALIFORNIA, A CORPORATION OF NEW JERSEY.

ORGANIZED APPARATUS FOR APPLYING AND SEALING LINED CAN ENDS TO CAN-BODIES.

1,368,977.

Specification of Letters Patent. Patented Feb. 15, 1921.

Application filed August 17, 1916. Serial No. 115,497.

To all whom it may concern:

Be it known that I, IVAN D. THORNBURGH, a citizen of the United States, residing at Oakland, in the county of Alameda and 5 State of California, have invented certain new and useful Improvements in Organized Apparatus for Applying and Sealing Lined Can Ends to Can-Bodies, of which the following is a specification.

10 The hereinafter described invention relates to an organized apparatus for applying and sealing lined can ends to can bodies, and the invention is designed for use in the assembling and applying of can ends to that 15 type of cans known in the art as "sanitary cans," or those wherein the hermetically sealed joint between the can end flange and the flanged ends of the can body is closed or formed by a gasket liner interposed between the flange of the can end and the flanged end wall of the can body.

Of late it has been proposed to preserve food products in that type of cans wherein the entire bottom of the can is removable 25 for the purpose of withdrawing the contents from the container. The can bodies are supplied to the canners with one end, or what shall hereafter be termed the bottom end applied thereto, the top end being left off of 30 the can in order that the canner may place the food products therein to be preserved. With this type of can it has been found heretofore impracticable to automatically assemble the gasket lined bottom to the can 35 body, due to the fact that, contrary to the usual practice of applying can ends to can bodies, it is required that instead of the can end being brought down onto the can body, the body must be brought down onto the 40 gasket lined can end. The reason for this is owing to the fact that in connection with this type of can body, the gasket lined end is a non-curved end, hence, if the can end be placed in an inverted position, the gasket liner will drop or fall from the can end 45 flange.

The present invention therefore resides in 50 an automatic organized apparatus for placing gasket lined can ends and can bodies in axial alined position and preferably with the can body uppermost and held separate and supported a slight distance above the gasket lined can end, with means for conveying the axial alined can body and end 55 to assembling position onto a horizontally

disposed, freely rotatable disk, with means for clamping the can body and end to said disk for free rotation, combined with mechanism for uniting the flange of the can end to the can body, and where utilized for the 60 end closure of the type of cans before mentioned, the uniting of the can end to the can body comprises means for feeding a sealing strip relative to the flanged end of the can body and the flange of the can end 65 and applying the sealing strip to the flanged end of the can body and the flange of the can end during the free rotation thereof, whereby the sealing strip is securely clamped to said parts for holding the same in locked 70 position.

In brief, the apparatus comprises in its preferred embodiment, a reciprocating feed slide for receiving and delivering the can ends into the initial assembling position, 75 combined with a horizontally reciprocating feed slide working in unison therewith and preferably at right angles to the line of travel of the can end feed slide, for bringing can bodies from the feeding mechanism 80 into axial alinement with the can end at the initial assembling station of the apparatus, and means for transferring the axially alined can body and end from the initial assembling station to the assembling station 85 of the apparatus, during such transfer movement the said can body and end moving in unison and the can body being accurately brought downwardly onto the can end, so that when the initial assembling position has 90 been reached, the flanged end of the can body will rest on the flanged end of the can bottom, with mechanism for clamping the can body and bottom so assembled and holding the same in such assembled position for 95 free rotation, and means for uniting the lined can end with the can body, such means as shown herein applying, during the rotary movement of the clamped can body and end, a sealing strip for securely uniting the 100 flange of the can bottom to the flanged end of the can body.

In the apparatus as hereinafter set forth, gasket liners are applied to the flange of the can bottom, the gasket liner being either 105 cut from a disk blank of proper size or else cut from a traveling web of gasket material; in the present case, however, the ring liners are illustrated as being cut from a disk blank, which blanks are fed succes- 110

sively from a stack of blanks into the pockets of a rotatable turret and while held in said pockets the gasket liner is cut from the disk of gasket material, and thereafter, 5 by a part rotation or step movement imparted to the said turret, the gasket liner is brought into axial alinement with an unlined can end fed from a stack of unlined can ends into the pocket of the turret containing the said ring liner. It is obvious, 10 however, that the gasket lined can ends or bottom ends may be fed within the sphere of the can end feed slide from a stack of gasket lined can ends. It will therefore be 15 understood that the invention contemplates either the cutting of gasket liners from disks of gasket material or from a web of gasket material, and bringing the same into axial alinement with an unlined can end and applying the gasket liner to the said unlined 20 can end or bottom prior to the same being delivered to the can end feed mechanism, and equally so, the delivery of a gasket lined can end within the sphere of a can end 25 feed mechanism.

It will be understood in the carrying out of the invention that the various interconnected or assembled working parts of the apparatus are automatic in their operation 30 and work in timed relation one with the other so as to come into action at the proper moment for the carrying out successively of the various steps incident to the operation just described.

35 The sealing strip employed in connection with the closing of the can bottom to the can end is formed of such material as to be easily unwound or removed from the container to permit the sealed can bottom to be 40 readily detached or removed from the container, and in connection with the sealing strip feed mechanism there is embodied means for accurately forming the same into a U-shape or trough-like form so that when 45 the same is brought into position relative to the assembled can body and bottom, the said strip will embrace the upper surface of the flanged portion of the can body and the lower surface of the flange of the can 50 bottom, so that when pressure is applied to the two surfaces of the sealing strip, the same are firmly pressed onto the flanged surfaces of the can body and can end.

In order to comprehend the invention, 55 reference should be had to the accompanying sheets of drawings, wherein—

Figure 1 is a front elevation of the parts in assembled position, disclosing can bodies being fed into the machine, and the sealing 60 strip being fed to the forming rolls, also disclosing the rotatable turret for conveying gasket liners and can ends to the can end feeding mechanism, and illustrating in general the drive mechanism for the various 65 working parts of the apparatus and the

punch or die mechanism for cutting the ring liners from the gasket material and the assembling plunger for applying the gasket liner to the flange of a can end.

Fig. 2 is a plan sectional view taken on 70 the irregular line 2—2 of Fig. 1 of the drawings, said view disclosing the rotatable turret, the feed mechanism for an unlined can end, the feed mechanism for the can bodies, the reciprocating slides for conveying gasket lined can ends and can bodies to the initial assembling station, the means for transferring said can bodies and ends from axially alined position to the assembling position, feed rolls and forming rolls for the 75 sealing strip, the rolls for compressing the said strip onto the flanges of the assembled can body and end, and the means for ejecting the sealed can body from within the apparatus.

Fig. 3 is a vertical sectional view with parts shown in full, taken on line 3—3 of Fig. 1 of the drawings and viewed in the direction of the arrow, said view illustrating more clearly the gasket liner cutting 90 mechanism with the discharge for the cut core piece removed from the gasket material during the cutting of the ring liner therefrom.

Fig. 4 is a vertical sectional view with 95 certain parts shown in full and certain parts removed for clearness of illustration, said view being taken on the irregular line 4—4 of Fig. 1 of the drawings and viewed in the direction of the arrow, disclosing more 100 fully the feed mechanism for delivering the disk blanks within the pockets of the rotatable turret, and the feed mechanism for delivering unlined can ends into said pockets beneath and in axial alinement with the 105 ring liner contained within said pocket, and further illustrating the means for actuating the said mechanism.

Fig. 5 is a broken vertical sectional view 110 of the can end feed mechanism taken on line 5—5 of Fig. 4 of the drawings and viewed in the direction of the arrow.

Fig. 6 is a broken horizontal sectional plan view with parts removed for clearness of illustration, the said view being taken on 115 the irregular line 6—6 of Fig. 1 of the drawings and viewed in the direction of the arrow, said view illustrating the reciprocating feed slides for placing can bodies and the lined can ends in axial alinement at the 120 initial assembling position of the apparatus, and disclosing the mechanism for operating the said slides in unison.

Fig. 7 is a longitudinal sectional view with parts shown in full taken on line 7—7 of 125 Fig. 6 of the drawings and viewed in the direction of the arrow, said view illustrating the means for forcing a cut ring liner from within its seat of the rotatable turret and applying the same to the flange of a positioned 130

can end, also illustrating a can body and a gasket lined can end in axial alinement at the initial assembling station of the apparatus, and further illustrating the rotatable 5 clamps at the assembling station for holding the can body and the can end in assembled position during the operation of applying the sealing strip thereto, and further illustrating a sealed can body as being discharged 10 from the apparatus.

Fig. 8 is a view similar to Fig. 7, illustrating the knock-out portion of the gasket ring applying plunger in lowered position and holding a gasket lined can end onto the 15 reciprocating feed slide, which has been partially moved inwardly, said feed slide being partly in section and illustrating a gasket lined can end and can body in axial alinement and being carried part way toward the assembling station.

Fig. 9 is a sectional view, parts being shown in full, taken on the line 9—9 of Fig. 1 of the drawings and viewed in the direction of the arrow, said view illustrating the 25 gasket liner assembling plunger in raised position, the can end within one of the pockets of the rotatable turret, and disclosing the no-end detector associated with each of said pockets and the device thrown into action 30 thereby for locking the reciprocating feed slides against movement in case a lined can end is not present within the pocket of the turret when brought within the sphere of the can end feed mechanism.

Fig. 10 is a transverse sectional view taken 35 on line 10—10 of Fig. 1 of the drawings and viewed in the direction of the arrow, illustrating the Geneva drive for actuating the parts in timed relation, disclosing the feed 40 slide for moving or transferring the can body from its feed mechanism into the initial assembling position, and the feed slide for transferring an axially alined can body and end from initial assembling position to 45 assembled position, said view further illustrating the no-can and the no-end control mechanism for the feed slides.

Fig. 11 is a transverse sectional view, taken 50 on line 11—11 of Fig. 1 of the drawings and viewed in the direction of the arrow, said view disclosing more clearly the can body detector and the can end detector control.

Fig. 12 is a horizontal sectional plan de- 55 tail view taken on line 12—12 of Fig. 1 of the drawings and viewed in the direction of the arrow, disclosing the rock shafts actuated by the detector mechanism for controlling the actuation of the feed slides in accordance as to whether there is a can body or a 60 gasket lined can end in position for feeding to the initial assembling station of the apparatus.

Fig. 13 is a transverse sectional view, cer- 65 tain parts being shown in full, taken on line

13—13 of Fig. 1 of the drawings and viewed in the direction of the arrow, disclosing the sealing rollers for applying the formed sealing strip to the flanges of the assembled can body and end, and the mechanism for 70 actuating the same, and also further illustrating the means for actuating the vertical movable clamp chuck for clamping the assembled can body and end and holding the same so clamped during the operation of 75 applying the sealing strips; also illustrating the means for actuating the knock-out or ejector device for the sealed can body.

Fig. 14 is a fragmentary sectional view taken on line 14—14 of Fig. 1 of the drawings and viewed in the direction of the arrow, disclosing the feed rolls for delivering the sealing strip to the form rollers, the drive mechanism for said feed rolls and the reciprocating knife for cutting the sealing 85 strip into proper length as fed toward these feeding rolls.

Fig. 15 is a view taken on line 15—15 of Fig. 1 of the drawings and viewed in the direction of the arrow, illustrating the primary forming rolls for the sealing strip and the drive mechanism for actuating the 90 said rolls.

Fig. 16 is a view similar to Fig. 15 taken on the sectional line 16—16 of Fig. 1 and 95 viewed in the direction of the arrow, illustrating the final forming rolls for the sealing strip and the mechanism for actuating the same, also disclosing the can body on the endless carrier for feeding the same to the 100 reciprocating can body feed slide.

Fig. 17 is a fragmentary sectional view taken on line 17—17 of Fig. 1 of the drawings and viewed in the direction of the arrow, illustrating the discharge means and 105 the discharge runway for the sealed can.

Fig. 18 is a horizontal section of the ring liner cutting die on line A—A of Fig. 3.

Fig. 19 is a perspective view illustrating the dies for cutting off the sealing strip. 110

In the drawings, the numeral 1 is used to designate any suitable form of a frame capable of sustaining the various working parts of the apparatus, which frame in the present case comprises a suitable base plate 115 2 and upwardly extending frame pieces 3 and 3'; a horizontally disposed drive shaft 4 is journaled in suitable bearings 4' supported by the upper end portions of the frame pieces 3 and 3' and the central upwardly extended portions of the frame 1, and the said drive shaft 4 at one end carries the belt pulley 5 to which power is applied in any suitable manner and its opposite end has secured thereto a bevel gear 6, which gear 120 meshes with a similar gear 7 secured to the upper end of a vertically disposed shaft 8, which shaft turns in guide bearings 9 carried by the brackets 9' projected from the frame piece 3, and the said shaft 8 at its 125 130

lower end carries a beveled gear 10 which meshes with a beveled gear 11 secured to the outer end of a horizontal shaft 12, Fig. 1 of the drawings.

- 5 A horizontally disposed shaft 13 journaled in suitable bearings in the frame of the machine and arranged parallel with and a short distance above the horizontally disposed shaft 12, receives or has imparted thereto intermittent rotation from the said shaft 12 through the medium of a Geneva wheel 14, secured to the said shaft 13 and which Geneva wheel 14 is actuated by the Geneva arm 15 secured to the shaft 12, said 15 Geneva arm 15 carrying at its upper end the roll 15' which works in and out of the radial slots of the Geneva wheel 14, Figs. 1 and 10 of the drawings.

On the outer end of the shaft 13 is secured 20 a miter gear 16, which said gear meshes with a miter gear 17 secured to the lower end portion of the vertical shaft 18, journaled in suitable bearings of the machine, and the said shaft 18 at its upper end has secured thereto a horizontally disposed rotatable 25 turret 19 which rests upon a table 20 secured to the frame of the machine, Figs. 1, 3 and 4 of the drawings.

As will be seen by reference to Fig. 3 of 30 the drawings, the pitman 21 operating on a crank 22 formed in the drive shaft 4 is pivotally connected to a vertical movable slide 23 working within the vertical guide ways formed in the frame piece 23' and at its 35 lower end the said slide 23 carries a cutting die 24. The die 24 is surrounded by a stripper ring 25, which stripper ring is normally held in a downward position by means of the springs 26 seated within the die head 40 24'; a pitman 27 similar to the pitman 21 operating on the crank 28 formed in the shaft 12, is pivotally connected at its free end to a slide 29, which works in guideways formed in the frame piece 29'. The said 45 slide 29 at its upper end carries a cutting die ring 30, which said die ring is arranged in axial alignment with the cutting die 24 and cooperates therewith during the action of cutting a gasket liner from the gasket material from which it is formed. The said cutting ring 30 normally rests within a die opening 30' formed in the table 20.

Said horizontally rotatable turret 19 is provided circumferentially with a plurality of vertically disposed pockets 31 which pockets are adapted to be successively brought into registry with the die opening 30' of the table 20 and in axial alignment with the cutting dies 24 and 30.

60 Referring to Figs. 2 and 4 of the drawings, it will be noted that there is provided above the horizontally disposed table 20 a suitably constructed disk blank holder 32, which is adapted to contain a stack of horizontally disposed disk blanks 33 formed of gasket

material, and the said blank holder 32 in the present case is upwardly projected from a suitable centrally apertured base plate 34 secured to the upper surface of the table 20 and adjacent to the rotatable turret 19. 70 Associated with the said holder 32 is a reciprocating feed slide 35, which operates in ways 36 of the base plate 34.

The said slide 35 is provided at its inner end with a cut-out knife or blade 38 which, 75 during the inward stroke of the said slide, moves between the lowermost disk of the stack of disks and the disk immediately thereabove and cuts out the said lowermost disk and moves the same inwardly through 80 the radial opening 33' of the turret opening 31, and on its backward stroke leaves the disk blank within said opening and seated on the circumferential shoulder 31'. The said slide 35 is actuated by a lever 40 connected 85 thereto by a link 39 at its upper end, the said lever 40 being pivoted at 41 to the base plate 2 of the machine, and the said lever 40 has pivoted thereto, adjacent its lower end, a connecting rod 42. This rod at its inner 90 end is connected to a yoke 43 which carries a cam follower roll 44 operating or working in a cam groove 45 cut in one face of a vertical cam 46 secured to the horizontal shaft 12. The action of the cam 46 on the 95 slide 35 through the medium of the described connection, advances the said slide toward the turret 19, thereby carrying the knife or cut-out blade 38 between the two lowermost blanks of the stack of blanks 100 contained within the holder 32 for the removal of the lowermost blank and the positioning of the same as described on the circumferential ledge or shoulder 31' formed in the pockets 31 of the turret 19.

At another portion of the horizontally disposed table 20, and preferably opposite that at which is situated the holder for the disk blanks, is located a can end holder 47 which, like the holder for the disk 110 blanks, is upwardly projected from a centrally apertured base plate 48, the said holder 47 being adapted to contain a stack of horizontally disposed can ends 50. The said base plate 48 of the holder 47 is secured to a frame piece 49, supported by the table 20 and brackets 49' projected from the frame of the machine. The can ends are successively removed from within the holder by means of the reciprocating slide 51 which 115 slide is connected by a link 52 to the operating lever 53, which lever is pivoted at 54 to the base plate 2. To the said lever 53 adjacent its lower end is pivotally connected a rod 55 which, at its other end, is secured to a yoke 56 which carries a cam follower roll 57 operating within a cam groove 58 cut in the face of the cam 46 opposite to that in which is cut the cam groove for the roll 44. The said slide 51 is provided with 120

125 130

cam inclined portions 59 which on the inward stroke of the said slide 51 act upon the rollers 60 carried by the levers 61, which levers are pivoted at 62 to the frame piece 5 49, the said rollers 60 being held inwardly against the cam surfaces 59 by the tension of the spring 63, which is connected to the outer ends of the pivoted levers 61, Figs. 2 and 5 of the drawings.

10 At their inner ends the levers 61 carry the inwardly projected adjustable cut-out plates or fingers 64, which operate or move within the opening 65 cut in the base plate 48 of the can end holder, and the said cut-out 15 plates or fingers are provided with the incline surfaces 66, so that during the inward movement of the inner end portion of the pivoted levers 61 the said blades move between the two lowermost can ends of the 20 stack of retained ends and separate and cut out the lowermost can end from the said stack of ends contained within the holder 47, the action of the incline faces of the cut-out fingers being to lift the entire body of 25 the stack of can ends with the exception of the lowermost end of the stack.

It will clearly be seen by reference to Fig. 4 of the drawings, that the cam 46 operates the can end cut-out feed slide 51 through 30 the medium of the described connections, lever 53, rod 55 and yoke 56, and that on the forward feed of the said slide the lowermost can end is cut out from the stack of ends and moved inwardly and deposited into the 35 turret opening 31 through the radial opening 31² on the under side of the turret, and is deposited within said opening of the turret immediately beneath and in axial alinement with the cut ring liner situated therein.

40 It will be understood that the cutting die mechanism heretofore described and illustrated in Fig. 3 of the drawings is located or situated intermediate of the disk feed mechanism and the described can end feed 45 mechanism, so that as the turret 19 is rotated to carry a disk of gasket material from the disk feed station toward the can end feed station, the cutting mechanism comes into action at a moment of rest of the 50 rotatable turret for acting on the disk of gasket material situated within one of the openings of the rotatable turret brought into alinement with the cutting dies and severs therefrom a gasket ring of proper 55 size. The next rotation of the turret 19 places the pocket or opening carrying the ring liner into position beside the can end feed mechanism, for permitting the can end to be delivered from the stack of can ends 60 into the said pocket beneath and in axial alinement with the cut ring liner.

65 For convenience, it is here stated that the mechanism just described comes into action prior to a gasket lined can end being brought within the sphere of the feed mech-

anism or reciprocating slide for conveying the same to the primary assembling station, and in Fig. 2 of the drawings the station at which the disk of gasket material is delivered into one of the pockets of the rotatable turret is designated by the reference letter C, and the station at which the ring liner or gasket liner is cut from said gasket material at a subsequent stage of the turret's rotation, is designated by the reference letter D, and the station at which the unlined can end is conveyed into the pocket of the turret beneath and in axial alinement with the cut ring liner, is designated by the reference letter E, and the station at which the assembling of the cut gasket liner relative to the flange of the can end as performed at a subsequent step of the turret's rotation is designated by the reference letter F.

70 Referring more particularly at this point to the feed of the sealing strip and the formation of the said strip for applying same to the flanges of the assembled can body and end, and which mechanism appears in Figs. 1, 2, 14, 15 and 16 of the drawings, the reference numeral 67 designates a horizontally disposed shaft journaled in bearings of the frame of the machine and held in longitudinal alinement with the horizontally disposed shaft 13, more clearly seen in Fig. 1 of the drawings. The said shaft 67 carries at its inner extremity a cone clutch member 68 which is adapted to move into a recessed wall 69 of a disk clutch member 70, which said member 70 is feathered upon the shaft 13. Normally, the said disk clutch member 70 is held away from the clutch member 68 by the tension of a spring 71, located between the ends of the shafts 67 and 13, Figs. 1 and 13 of the drawings. The said disk clutch member 70 is provided on the periphery thereof with an annular groove 72, which is normally positioned in line with a cam disk 73, affixed to the shaft 12, and the said cam disk 73 is formed on its periphery with a cut-out portion 74, which cut-out portion during each revolution of the disk 73 clears the lower edge of the disk 70 and permits the same to slide inwardly toward or outwardly away from the cone clutch member 68. The function of the said disk 73 is to lock the disk 70 forward or backward, as the case may be, relative to the cone clutch member 68.

75 It is the rotation which is transmitted at proper intervals or in proper timed relation from the shaft 13 to the shaft 67 through the medium of the described clutch mechanism which, in turn, transmits motion to the respective drive means to actuate the feed and forming rolls for the sealing strip, as will be hereinafter more fully set forth.

80 At the assembling station F, Fig. 2 of the 130

drawings, for applying the cut gasket liner to the flange of a positioned unlined can end, is situated the assembling mechanism, and which appears more clearly in Figs. 1, 5 7, 8 and 9 of the drawings.

- Referring more particularly to Figs. 1 and 9 of the drawings, it will be noted that a cam 75 secured to the upper horizontally disposed drive shaft 4, and which is provided with a cam groove 76 in one face thereof, operates during the rotary movement of the drive shaft 4 upon a cam follower roll 77 secured to the lower extremity of a yoke 78, which said yoke is connected to a rod 10 79, the said rod carrying at its lower extremity a plunger 80, which is in axial alinement with one of the pockets 31 of the turret 19 during a rest moment of the said turret, the said plunger 80 being held normally 15 above the surface of the rotatable turret 19. This plunger or plunger head is formed with a downwardly extended annular extremity 80' which, during the downward movement of the said plunger, is adapted 20 to move within the opening 31 of the turret in axial alinement therewith, and said plunger head 80 has connected thereto and within the annular projection 80' thereof, an 25 ejector plate 81 which is held to the plunger head by a stud 82, and the said ejector plate is normally held downwardly away from the plunger head by means of the tension of the springs 83 seated within recessed sockets formed in the under surface of the 30 plunger 80 and the upper surface of the ejector plate 81. As the plunger head 80 is moved downwardly by the action of the cam 75 and its controlled mechanism, the lower extremity of the extension 80' removes the 35 cut ring liner from off the annular ledge or shoulder 31', on which it rests within the pocket 31 of the turret and carries the same downwardly below the said ledge and deposits it onto the flange of the can end contained within said pocket of the turret 19, 40 Figs. 7 and 8 of the drawings.

The moment the gasket liner has been applied to the flange of the can end, the plunger commences its return or upward stroke, 45 but through the action of the springs 83, the ejector or follower 81 by its retarded movement, due to the pressure of the said springs, holds the lined can end down onto and against the upper face of the horizontally reciprocating slide feed plate 86, which slide plate operates within guide ways 87 formed in the table 20. Inasmuch as the feed slide 86 is provided at its outer end with an upwardly projected shoulder extension 88, the 50 said extension or shoulder will engage the outer circumferential edge of the can end and serve to forcibly push the can end inwardly with the forward stroke of the said feed slide, thereby removing the lined can

end from within the sphere of the rotatable 55 turret, and advancing the same to a point a slight distance beyond the said rotatable turret. During this inward stroke of the feed slide the gasket lined can end is moved beneath a retaining spring 88' which exerts a 70 downward pressure on the said lined can end and prevents the same being moved outwardly on the return stroke of the said feed slide, and on the full return of the said feed slide, to lower the lined can end onto the face 75 of the table 20 so as to place its outer wall edge in line with the notched forward end 88² of the reciprocating feed slide. The gasket lined can end is thus placed so as to be engaged by the forward notched edge or 80 end 88² of the feed slide on its next forward stroke to be moved thereby from its position of rest. At this point the gasket lined can end is in axial alinement with a can body, which has been brought into initial assembling position by means of the hereinafter described mechanism, and it is held separated 85 from the said can body by a supporting plate on which the said can body rests. It is from this position that the lined can end 90 and the can body are moved to assembling position by the next forward stroke of the reciprocating feed slide; the notched inner end 88² of the feed slide is at such time engaging the can end and advancing and 95 moving the same onto the lower rotatable member of the clamping means for the can body and end. Preferably, the can body is moved inwardly to the clamping means in synchronism with the lined can end, and in 100 order that this may be accomplished as a single operation, the slide plate 89 to which is connected the reciprocating feed slide 86 by means of a web 89' (Fig. 10 of the drawings), is provided with an upwardly projected bracket or arm 86' which works within the longitudinally slotted portion 87' of the table 20. The said arm 86' is provided with an angularly disposed overhang extension 86², projected inwardly to overlie the 105 reciprocating feed slide 86 and at a height sufficiently above the same to engage with the rear wall surface of a positioned can body 103, a slight distance above the bottom thereof. By means of this construction, as 110 the feed slide 86 is moved inwardly to carry a lined can end from the initial assembling station G to the assembling station H, the overhang extension 86² of the bracket or arm 86' engages the rear wall surface of the 115 can 103, and moving with the slide 86 advances or moves the can body in unison with the movement of the lined can end, so that the said can end and the can body are brought to a state of rest at the assembling 120 station at one and the same time and in axial alinement.

As shown in Figs. 6, 7, 8 and 10 of the

- drawings, the actuating plate 89 to which is attached the can end feed slide 86, is provided on one edge thereof with a rack portion 91, which rack portion of the plate 89 meshes with a gear 92, mounted upon a vertical shaft 93, journaled in suitable bearings in the frame of the machine, and the said gear 92 in turn meshes with a segment rack 94 secured to a vertical shaft 95, journaled in suitable bearings in the frame of the machine. In its upper end portion the shaft 95 is provided with a vertical slot and clutch member 96 (Fig. 10) within which normally fits the tooth portion 97' of the sliding block 97 feathered on the shaft 98, projected at its lower end within the upper extremity of the clutch member 96, and which shaft is journaled in suitable bearings of frame 1 of the machine. The tension of a spring 97' normally holds the block 97 in locked engagement with the clutch 96. The shaft 95 is a rock shaft and rocking motion is imparted thereto through the medium of the crank arm 99 secured to the upper end portion of the shaft 98, the said crank arm at its outer end portion carrying a follower roll 100, which works within a cam groove 101 cut in the periphery of the disk 102 secured to the horizontal drive shaft 4.
- 30 The can body 103 to which the end or bottom is to be applied is fed into the machine and brought to the station designated by the reference latter A in Fig. 2 of the drawings, by means of the endless carrier belt 104, which belt moves over the table 20 and passes over the idler roll 105, journaled in the under surface of the table, Figs. 2, 6, 7 and 10 of the drawings. The said carrier belt is continuously driven by any suitable mechanism, not shown in the drawings, and adjacent to the said carrier belt 104 at the inner extremity thereof, as shown more clearly in Fig. 2 of the drawings, there is located a horizontally reciprocating feed slide 106, which works in guide ways 107, and in the present case its movement is at right angles to the direction of travel of the reciprocating can end feed slide 86. The said slide 106, like the slide 86, is provided with a rack tooth portion 108, Fig. 6 of the drawings, which meshes with a gear 109 mounted on a fixed stud 110 upwardly projected from the table 20, and the said gear 109 also meshes with a rack segment 111 which, like the rack segment 94, is secured to and works with the vertical shaft 95.
- At the inner extremity of the runway for the incoming can bodies 103, is located a transverse wall plate 112, which acts as a stop for the inward moving can bodies and to hold the innermost one thereof at rest in line with the reciprocating slide 106. When a can body is in this position, the inward stroke of the slide 106 moves the said can body inwardly transversely, carrying
- the same from off the endless carrier 104 and depositing the same onto the supporting plate 113 under which the gasket lined can end is brought, so that the can body and the casket lined can end stand in axial alinement, 70 but separated by the plate 113 which, at such time, supports the can body. During the movement of the can bodies by the endless carrier toward the barrier wall 112, the same move beneath the gage plate 114, which 75 serves to prevent the can bodies from moving out of adjusted position so as to be held down during the inward movement thereof by the feed slide 106, Fig. 2 of the drawings. The can body as moved into initial assembling position and onto the supporting plate 113, moves beneath the hinged guide plate 115, Fig. 10 of the drawings, which plate is pivoted at 116 to a bracket 117 upwardly projected from the table 20, the weight of 80 the said hinged plate 115 serving to hold the can body in its position relative to the supporting plate 113 and serving at the same time to hold the can body in its proper position relative to the gasket lined can end as 85 the said can end and the can body are moved to assembled position on the inward stroke of the reciprocating feed slide 86, the gage plate 118 attached to the bracket 117 serving, with the plate 115, to properly guide the can 90 body during its movement to assembling position.
- By reference to Fig. 10 of the drawings, it will be noted that the hinged guide plate 115 is prevented from moving downwardly 100 beyond a given distance by means of the lip extension 119 projected from the bracket 117.
- By reference to Fig. 2 of the drawings, it will be observed that the runway for the infeed of the can bodies to the station A is 105 formed by the parallel bars 120, which are held above the table 20 by suitable supporting brackets 121.
- Referring now to the feed mechanism for the sealing strip, Figs. 1, 2, 14, 15 and 16, 110 it will be noted that the strip of sealing metal which consists of a thin pliable strip 122, is wound upon a spool 123 which is mounted upon a stud 124 which is affixed to the table 20. This is a continuous sealing strip and 115 is delivered by the feed rolls 125 and 126 to the form rolls. These feed rolls are mounted respectively upon the spaced vertical shafts 127 and 128 which are mounted in suitable journals on the table 20 and are geared to 120 turn in unison by means of the gears 129 and 130 respectively, Fig. 14 of the drawings. The gear 131 which is secured to the lower extremity of the shaft 127 meshes with the gear 132 secured to the horizontal shaft 125 67, and imparts rotation to the shaft 127, the rotation of which, through the described meshing gears 129 and 130, imparts rotation to the shaft 128. The feed rolls 125 and 126 feed and deliver the sealing strip to the first 126

operation forming rolls 133 and 134, Fig. 15 of the drawings, which forming rolls are mounted respectively upon the shafts 135 and 136, which shafts rotate within suitable journals on the table 20 and are rotated in unison by the meshing gears 137 and 138 respectively. The gear 139 is secured to the lower extremity of the shaft 135 and meshes with the gear 140 secured to the horizontal shaft 67 and by means of which intermeshing gears, rotation is transmitted to the shaft 135, and from said shaft transmitted to the shaft 136 through the described meshing gears 137 and 138. The first set of forming rolls only partially form the sealing strip, and from said rolls said strip is delivered to the second set of forming rolls 141 and 142, which are mounted respectively upon the shafts 143 and 144, Fig. 16 of the drawings, and which shafts are rotated in unison through the medium of the gears 145 and 146 mounted respectively on the said shafts.

To the lower extremity of the shaft 143 is secured the gear 147, which meshes with the gear 148 secured to the horizontal shaft 67. Interposed between the feed rolls 125 and 126 and the first operation forming rolls 133 and 134, is located a reciprocating knife 149, Figs. 2 and 14 of the drawings, which knife works within a guide block 150 secured to the upper surface of the table 20 and the said knife is adapted to cut the sealing strip at predetermined times, as hereinafter described, which knife is normally held outward by the tension of the spring 151 and by means of a bell crank lever 152 pivoted at 153 to the table 20, the said lever being connected at its outer end to a longitudinally movable bar 154, the opposite end of the said bar in turn being connected by a pivoted lever 155 to the table 20 at the point 156, the free end of the said lever 155 being extended inwardly to lie within the path of the arm 86', so that when the said arm is moved longitudinally inwardly with the travel of the operating slide plate 89, the same as it approaches the end of its stroke will engage with the inner end of the said lever 155 to throw the same so as to actuate the rod 154 to force inwardly the knife 149 for severing the web 122 intermediate the feed rolls and the first set of forming rolls.

At a short distance beyond the second set of forming rolls 141 and 142 is located the sealing roll 157 (Fig. 13) which is attached to a shaft 158 journaled in suitable bearings formed on the under surface of the table 20, Fig. 13 of the drawings. To the outer end of said shaft 158 is secured a gear 159 which meshes with a gear 160 on the upper end portion of a vertical shaft 161, journaled in bearing brackets 162, secured to the frame of the machine and which at its lower end carries a gear 163, and

which gear 163 is secured to the lower extremity of the shaft 161 and meshes with a gear 164 mounted upon a shaft 165 journaled in brackets 166, secured to the base plate 2 of the machine.

On the shaft 165 is secured a beveled gear 167, which meshes with gear 168 carried by the shaft 12, Fig. 1 of the drawings. Above the sealing roll 157 is located a companion vertically rotatable sealing roller 169 which cooperates with the roller 157 for compressing the sealing strip onto the flanges of the clamped can body and end, Fig. 13 of the drawings. The roller 169 is carried by a shaft 170 which is journaled in a hinged bearing bracket 171, which bracket is pivoted at 172 to a fixed bracket 173 mounted on the table 20. To the outer end of the shaft 170 is attached a gear 174, which receives rotation from a gear 175 which is mounted on the shaft 158 and works through an opening in the table 20. The hinged bracket 171 carrying the shaft 170 is connected with a cap 177 secured to the upper end of a vertical slidable shaft 178 by means of a link 176, the said cap 177 carrying a cam follower 179 operating upon a cam 180 secured to the drive shaft, and is normally held upward by means of a spring 177' secured on the shaft 178 intermediate the cap 177 and the upper end of the guide bearing for the said shaft 178. The shaft 178, which is slidable within the guide bearing 178', carries at its lower extremity a plunger 181 which is freely rotatable on a stud 182, which holds the said plunger to the head of the shaft 178 and which plunger turns freely on the ball bearings 182' in position between the same and the said head of the shaft 178. Within a seat 183' of the table 20 is located or seated a circular disk 183, which disk is in axial alinement with the plunger 181 and is held in place relative to the table 20 by means of a supporting stud 184, the said disk turning freely on the anti-frictional balls 183' in position between a bearing plate 183' and the underface of said disk. The cam 185 secured to the shaft 161 intermediate of its length and provided with a cam groove 186, operates upon a cam follower 187 carried by a yoke 188, which yoke is connected by a rod 189 to the crank lever 190 secured to the lower end of a vertical shaft 191, which shaft carries at its upper extremity a can end positioner 192, which is provided with an ejector arm 193, Figs. 2, 6 and 13 of the drawings. The clutch mechanism heretofore described for transmitting motion from the shaft 13 to the shaft 67 is actuated by a lever 194, Figs. 1 and 7 of the drawings, which lever is pivoted at 195 to the frame of the machine and is normally held, outwardly pressed or in a backward position, by means of a spring 196 which is attached

at one end to the said lever and at its opposite end to the frame of the machine. This lever is provided with an extension 197 which is adapted to press against the sliding 5 clutch disk member 70 for controlling transmission of the rotation from shaft 13 to shaft 67. The upper end of the said lever 194 is in line with a lug 194' formed on the lower end of the rack 89, Fig. 7 of the drawings, so that the lever 194 is actuated by the slide movement of the said rack 89 which is carried by the slide 86.

Should there come a time during the operation of the feeding of a can end 50 or of 5 a can body 103 when there is no end in position for its associated can body, or when there is no body in position for its associated can end, it is necessary to hold the said end, or the said body, as the case may be, and prevent the same from moving toward the sealing mechanism until there is an associated body for an end and vice versa. The following mechanism is for such a purpose and comprises, broadly, a can body detecting 0 apparatus, a can end detecting apparatus, and mechanism associated therewith whereby should either the can body or the can end detecting apparatus be operated by reason of there being no body or end in position, the 0 sliding feed parts of the machine will cease to operate until the deficiency has been supplied.

As seen in Figs. 1 and 11, a cam 198 provided with a cam groove 198' is secured to the upper shaft 4, and said groove 198' operates upon a cam follower 199 secured to a yoke 199'. A sliding spindle 200 fastened to the yoke 199' slides within a bearing 200' formed in the frame 1 and is provided at its 0 lower extremity with a collar 201, and provided intermediate its length with a collar 201', both collars being rigidly fixed to said spindle. A spring 202 surrounds spindle 200 and is interposed between the upper surface 5 of collar 201' and the lower surface of a forked portion 203' of a lever 203, which is pivoted at 204 to the frame 1. Pivoted at 204' to the opposite end of lever 203 is rod 205 which slides vertically 0 within a guideway 206' formed in the frame 1, and said rod carries at its lower extremity a can body detecting shoe 205'.

A spring 206 surrounds spindle 200 and is interposed between the upper surface of the 5 collar 201 and the lower surface of a bushing 207 surrounding the spindle 200 and sliding within a chamber 207' formed in the frame 1 below the bearing 200'. It is obvious that a lifting of the spindle 200 by the 0 action of cam 198 as aforescribed, tends to lower the shoe 205' and also tends to raise the bushing 207. If, however, the shoe 205' is prevented from moving downward by reason of a can body 103 being below in its path 5 of travel, the spring 202 is compressed dur-

ing the full upward movement of the spindle 200. In like manner, if the bushing 207 is prevented from moving upward, by a reason hereafter to be described, the spring 206 is compressed during the full upward stroke 70 of the spindle 200.

Rack teeth 205² formed on one side of the rod 205, as shown in Figs. 11 and 12, mesh with teeth 208' cut in one side of a horizontal shaft 208 which rocks within a bearing 208² formed in the frame 1. As seen in Figs. 10 and 12, a cam 209 is secured to the opposite end of the shaft 208 and said cam lies directly beneath an extension 96' of the clutch member 97. If there is no can 103 in position beneath the shoe 205' (Fig. 11) to stop the downward travel of the rod 205, the shaft 208 is partially rotated through the toothed connections 205² and 208' and the cam 209 carried by said shaft lifts the clutch member 97 out of engagement with the mating clutch member 96 and no rotation is imparted to the shaft 95.

As seen in Figs. 11 and 12, rack teeth 210 formed on one side of the bushing 207 mesh with teeth 210' cut in one side of a horizontal shaft 211 which works within a bearing 211' formed in the frame 1. Said shaft 211 (see Figs. 9 and 12) is provided at its opposite extremity with an eccentric portion 212, which is encircled by a crank arm 213 connected with one end of a bell crank 214 which is pivoted at 215 to the frame 1. Said bell crank 214 is provided with a tapered finger portion 216 which is adapted to enter a channel 217, formed within the turret 19 adjacent to each pocket 31, as seen in Fig. 9. A sliding pin 218 seated within the channel 217 is normally held outward by means of the spring 219, as seen in Figs. 2 105 and 9. Secured to the shaft 211 intermediate its length, as seen in Figs. 10 and 12, is a cam 220 and said cam lies directly beneath an extension 221 of the clutch member 97. If there is no end 50 in the pocket 31, Fig. 110 9, to stop the inward travel of the pin 218, the shaft 211 is permitted to partially rotate and the cam 220 lifts the clutch member 97, Figs. 10 and 12, out of engagement with its mating clutch member 96 and the shaft 95 115 remains stationary.

It is necessary in case a gasket lined can end is contained within one of the seats of the rotatable turret and there is no can body in position to be fed to the initial assembling position or station of the apparatus, that the said lined can end be prevented from being delivered to the said initial assembling station and for this purpose it is required that the same be held or maintained within its seat of the rotatable turret 120 19. This is accomplished through the medium of a yoked lever 223 which is pivoted at 224 to the table 20 and which is normally held in an upward position with its upper 130

surface flush with the under face of the turret 19 by means of springs 225, Figs. 6, 7 and 9 of the drawings, the said spring held yoke lever 223 being interposed between the 5 reciprocating feed slide 86 and the under surface of the rotatable turret 19.

It will be understood that the reciprocating feed slide 86 is held at rest at such time as rotation is not being imparted to the 10 shaft 95, for controlling the action of the feed mechanism for the can bodies and the reciprocating movement of the slide 86, as set forth hereinbefore. Inasmuch as rotation is not imparted to the said shaft 96 15 when a can body is not in position for feeding to the initial assembling station, the said slide 86 will remain stationary or inactive at such times.

As the plunger 80 operates to apply the 20 gasket liner onto the flange of the can end and depress the lined can end from within its seat, the pressure thereof acting against the yoked lever 223 depresses the same to place the gasket lined can end within the 25 sphere of the projection 88 of the feed slide 86, but as no movement at such time is imparted to the said slide the can end is not engaged by the projection thereof. As the plunger 80 moves upwardly to normal position, the action of the spring pressed lever 223 raises or carries the gasket lined can end within the seat of the rotatable turret 19, from which it was removed by the downward action of the plunger 80. As the rotation 30 of the turret 19 is an intermittent one, motion or rotation is imparted thereto the moment the plunger 80 moves from within the seat thereof and the gasket lined end is moved therein, and the gasket lined end is 35 moved with the rotatable turret and carried toward a discharge opening 227. The spring held yoked lever 223 thus acts as a resilient support for the can end during the time that the gasket liner is being applied onto the 40 flanged portion of the said end and for the lined end as depressed from within its seat. To the table 20 below the turret 19 is secured a circular guide bar 226, Fig. 6 of the drawings, and the said turret is cut away 45 50 on its under surface as shown at 226' to clear the bar 226, Fig. 4 of the drawings, the purpose of which bar 226 is to hold the non-discharged can end within the pocket of the turret 19. The discharge opening 227 with- 55 60 in the table 20 is located within the path of travel of a non-ejected gasket lined can end carried by the rotatable turret, so that when the seat or pocket of the turret containing said non-discharged gasket lined can end is brought into registry with the said pocket 227, the said gasket lined can end will drop therethrough, Figs. 4 and 6 of the drawings.

As illustrated in Figs. 2, 6 and 17 of the drawings, there is provided, adjacent the assembling station H, a downwardly extended

inclined chute 228, into which chute the sealed cans 103 are discharged by the ejector arm 193, and by means of which chute the sealed cans are conveyed to any suitable position or place of deposit.

From the foregoing, the operation of the machine will be readily understood, the same in brief consisting of the following steps, viz:—

A lined can end and a can body to which the end or bottom is to be applied are first brought, by means of the reciprocating feed slides, into axial alinement at the initial assembling station G, at such time the can body being held in superimposed relation to the lined can end or bottom and held separated therefrom by means of the plate 113, Fig. 10 of the drawings. When the parts stand in this relation, the second inward stroke or movement of the feed slide 86 and the actuating plate 89 carrying the bracket or arm 86' transfers the lined can end or bottom and the lined can body from the station G to the assembling station H, during which movement or transfer of the parts the can body is gradually placed onto the lined can end or bottom as the same is placed onto the rotatable support 183. With the parts thus positioned, the plunger 181 descends to clamp the can body and lined can end to the disk or plate 183, the parts when thus clamped being held between the freely rotatable members 181 and 183.

It will be understood that as the can body is being brought into superimposed position relative to the lined can end or bottom and the parts conveyed in axial alinement from the initial assembling station G to the assembling station H, that the sealing strip 102 is fed by the feed rolls 125 and 126 and the forming rolls 134—135 and 141—142 to and between the sealing rolls 157 and 169, Fig. 13 of the drawings, so that by the time the can body and lined can end are clamped between the members 181 and 183, the sealing rolls begin the compressing of the U-shaped sealing strip onto the flanges of the held can body and lined end, and that during the compressing operation the said sealing rolls serve to impart rotary movement to the held can body and lined end, rotating therewith the members 181 and 183, which rotary motion is continued until the cut length or section of the sealing strip has been completely compressed circumferentially relative to the flanged end of the can body and the flange of the lined can end or bottom, when the upper sealing roll is raised or lifted, the action of the spring 177, the tension of which is released at such time by reason of the cam 180, having moved from within the sphere of the roll 179. When the upper sealing roll 169 is thus raised out of contact with the compressed sealing strip, rotation of the sealed

can ceases, and, at this time, through the medium of the before-described mechanism, a part turn or rotation is imparted to the shaft 191, and the ejector arm 193 carried by said shaft is moved or thrown to engage and eject the sealed can from off the plate 183 and into the discharge chute or runway 228.

It will be understood, as before stated, 10 that the action of the various working parts are in timed relation one with the other, so that each comes into action at the proper moment for the carrying out of the work designed therefor.

15 While the preferred embodiment of the invention has been described and illustrated, it will be understood that the invention is not confined or restricted to the detailed construction of the working parts shown 20 and described, but that the same may be modified or varied at the will of the operator of the machine; the essence of the invention residing in interrelated working instrumentalities for receiving and spacing a 25 can body in superimposed relation with a lined can end or bottom and bringing the said parts into axial alinement at a sealing station of the apparatus, and uniting the assembled parts one to the other to form a 30 hermetic seal through the medium of a sealing strip applied to the flanges by the pressure of sealing rolls or such other means as will compress the sealing strip circumferentially of the flanges of the can body and 35 lined can end or bottom. The means for feeding the lined can ends or bottoms and the can body have associated therewith mechanism for controlling the movement thereof in accordance as to whether there is 40 positioned for feeding a lined can end or bottom to which a can body is to be applied, or controlling the action of the said parts in accordance as to whether or not there is 45 a can body to be positioned for feeding relative to a lined can end or bottom.

The spirit and intent is to claim the invention as broadly as the state of the art will warrant, and this irrespective of the 50 detailed construction of parts interrelated for the carrying out of the invention.

Having thus described my invention, what I claim as new and desire to protect by Letters Patent is:—

1. An apparatus for the described purpose, the same comprising interconnected working instrumentalities for positioning a gasket liner relative to a can end and applying the same thereto, means for automatically feeding a lined flanged can end 55 and a flanged can body in axial alinement to an assembling station, and means situated adjacent said assembling station for applying and compressing a sealing strip to the flanges of the assembled can end and body circumferentially thereof for forming 60

a removable hermetic seal union therebetween.

2. An apparatus for the described purpose, the same comprising reciprocating feed devices for independently and automatically 70 delivering a lined flanged can end and a flanged can body in axial alinement to an assembling station, means situated adjacent said station for applying a removable sealing strip to the flanges of the assembled 75 end and body circumferentially thereof for forming a hermetic seal union therebetween, and mechanism connected with and operating in timed relation said can end feed devices and said strip applying means. 80

3. An apparatus for the described purpose, the same comprising interconnected working instrumentalities for automatically feeding a lined flanged can end and a flanged can body in spaced axial alinement to an 85 assembling station with the can body in superposed relation to the can end, a rotary support for said assembled end and can body, and rotatable means for holding the alined can body to the said can end, and 90 means situated adjacent the assembling station for compressing a removable sealing strip to the flanges of the can end and body circumferentially during rotation of the clamping and supporting means for said 95 members.

4. An apparatus for the described purpose, the same comprising interconnected working instrumentalities for independently and automatically feeding a lined flanged 100 end and a flanged can body in axial alinement to an assembling station, rotatable clamping means for receiving said alined members and holding the same in axial alinement during the operation of sealing, 105 and sealing means situated adjacent the assembling station for applying a removable sealing strip to the flanges of the clamped can end and body circumferentially during the rotary movement thereof. 110

5. An apparatus for the described purpose, the same comprising means for independently and automatically delivering a lined flanged can end and a flanged can body in axial alinement to an assembling station, 115 devices for clamping the can body to the said end and holding the same so clamped during the operation of hermetically sealing the end to the body, and mechanism situated adjacent the assembling station for 120 applying circumferentially and compressing a removable sealing strip to the flange of the clamped can end and body.

6. An apparatus for the described purpose, the same comprising, in combination, 125 interconnected working instrumentalities for positioning a gasket liner relative to a can end and applying the same thereto; means for automatically feeding a lined flanged can end to an assembling station; 130

- means for feeding a flanged can body to said assembling station in axial line with and superposed on said lined can end; and means situated adjacent said assembling station for applying and compressing a sealing strip around the flanges of the assembled can end and body circumferentially thereof, and thereby forming a removable hermetic seal union therebetween.
- 10 7. In a machine for uniting flanged can ends to flanged can bodies by means of an encircling binding strip, the combination of a member for moving flanged can ends to a uniting station; means for moving flanged can bodies to the same uniting station, and placing them into axial alinement and in contact assembly with said can ends, whereby the flanges of said can bodies and said can ends lie in close contact; means adjacent to said uniting station for applying a binding strip into an encircling position around said can body and can end flanges, to bind and hold them securely united; means for ejecting the united cans and can ends; and mechanism connected with and operating in timed relation said can end moving means and said strip-applying means.
- 15 8. In a machine for uniting flanged can ends to flanged can bodies by means of an encircling binding and sealing strip, the combination of automatic means for moving flanged cans and flanged can ends to a uniting station, and placing them into assembled relation at said station with their flanges lying in close contact one with the other; means at said station for holding said cans and can ends in such close assembled relation; together with means at said station for winding and applying binding and sealing strips around and upon the flanges of said cans and can ends, to permanently and securely unite them one to the other; means to eject said cans and can ends after uniting; and mechanism connected with and operating in timed relation said can end moving means and said strip-applying means.
- 20 9. In a machine for uniting flanged can ends to flanged can bodies by means of an encircling, binding and sealing strip, the combination of feeding means for advancing cans and can ends to a uniting station; means for clamping said cans and can ends together at said station; means at said station for applying a binding and sealing strip around and upon the superposed flanges of said cans and can ends to permanently and securely bind them one to the other; and mechanism connected with and operating in timed relation said can end advancing means and said strip-applying means.
- 25 10. An organized apparatus for the described purpose, the same comprising inter-connected working instrumentalities for po-
- sitioning a gasket liner relative to a positioned can end and applying the same to the flange thereof, positioning the lined can end and a can body in axial alinement, assembling the alined members and hermetically seaming the lined can end to the said can body, and a power mechanism combined and connected with said positioning and assembling and seaming instrumentalities and operating them in timed relation to produce seamed cans from individual gasket liners, can ends and can bodies.
- 30 11. In an apparatus for the described purpose, in combination, means for receiving and feeding a lined flanged can end and means for feeding separately from said can end a flanged can body to an assembling station in axial alinement, sealing mechanism situated adjacent said assembling station for applying and compressing circumferentially a removable sealing strip relative to the flanges of the can end and can body for the formation of a hermetic seal, and means controlling the feed of the can body when a lined end is not positioned for axial alinement therewith.
- 35 12. In an apparatus for the described purpose, in combination, means for receiving and feeding a lined flanged can end and means for feeding separately from said can end a flanged can body to an assembling station in axial alinement, sealing mechanism situated adjacent said assembling station for applying and compressing circumferentially a removable sealing strip relative to the flanges of the can end and can body for the formation of a hermetic seal, and means controlling the feed of the can end when a flanged can body is not positioned for axial alinement with a lined can end.
- 40 13. In an apparatus for the described purpose, the same comprising means for receiving and feeding a lined flanged can end and a flanged can body to an assembling station in axial alinement, sealing mechanism situated adjacent said assembling station for applying and compressing circumferentially a removable sealing strip relative to the flanges of the can end and can body for the formation of a hermetic seal, and interconnected devices for controlling independently the feed of a lined can end and a flanged can body in accordance as to whether there is a can body positioned for assembling with a lined can end and vice versa.
- 45 14. An apparatus for the described purpose, the same comprising can end feed means for delivering a lined flanged can end to an initial assembling station, means for delivering a can body to said station in axial alinement with said can end, means carried by the can end feed means for moving the axially alined can body in unison with the can end to an assembling station, mechanism situated adjacent said station

for applying and compressing a removable sealing strip circumferentially of the flanges of the alined can body and end, and mechanism connected with and operating in timed relation said can end feeding means and said strip-applying means.

15. An apparatus for the described purpose, the same comprising a can end feed means for delivering a lined flanged can end to an initial assembling station, means for delivering a can body to said station in axial alinement with said can end, means carried by the can end feed means for moving the axially alined can body in unison with the can end to an assembling station, mechanism situated adjacent said station for applying and compressing a removable sealing strip circumferentially of the flanges of the alined can body and end, and devices thrown into action on the completion of the sealing operation for ejecting the hermetic sealed can body.

16. In an apparatus for the described purpose, the combination with mechanism for applying a sealing strip to the flanges of an assembled lined can end and can body, of coöperating working instrumentalities for separately positioning a can end and can body into alinement within the sphere of the sealing mechanism, and means for controlling the feed for the sealing strip in accordance as to whether an assembled can body and end is at the assembling station.

17. In an apparatus for the described purpose, the combination with mechanism for applying a sealing strip to the flanges of an assembled lined can end and can body, of coöperating working instrumentalities for separately positioning a can end and can body into alinement within the sphere of the sealing mechanism, and means for automatically feeding a sealing strip to said sealing mechanism, and means for controlling the feed for the sealing strip in accordance as to whether an assembled can body and end is at the assembling station.

18. In an apparatus for the described purpose, the combination with can end feed mechanism and can body feed mechanism for delivering a lined flanged can end and a flanged can body to an initial assembling station and in axial alinement, of a supporting device situated at said station for receiving and holding the can body separated from the can end, means carried by the can end feed mechanism for advancing the can body from the initial assembling station to an assembling station in unison with the movement of the can end to said station and in axial alinement therewith, rotatable devices situated at said station for holding the can body clamped to the can end, sealing mechanism adjacent the said assembling station for compressing a sealing strip circumferentially of the flanges of the can end and

body, and actuating mechanism connected with and operating in timed relation said can end feed mechanism and said strip-compressing mechanism.

19. In an apparatus for the described purpose, the combination with means for applying a gasket ring liner to the flange of a can end, can end feed mechanism for conveying the lined can end to an initial assembling station and from said station to an assembling station, mechanism co-acting with the can end feed mechanism for delivering a can body to the initial assembling station and in axial alinement with the can end, means situated at the initial assembling station for receiving and holding the can body separated from the can end, a device carried by the can end feed mechanism for transferring the can body from the initial assembling station to the assembling station in unison with the movement of transfer of the can end, sealing mechanism situated adjacent the assembling station for applying a sealing strip to the flanges of the axially alined can end and body, and actuating mechanism connected with and operating in timed relation said can end feed mechanism and said strip-applying mechanism.

20. In an apparatus for the described purpose, the combination with means for applying a gasket ring liner to the flange of a can end, can end feed mechanism for conveying the lined can end to an initial assembling station and from said station to an assembling station, mechanism co-acting with the can end feed mechanism for delivering a can body to the initial assembling station and in axial alinement with the can end, means situated at the initial assembling station for receiving and holding the can body separated from the can end, a device carried by the can end feed mechanism for transferring the can body from the initial assembling station to the assembling station in unison with the movement of transfer of the can end, sealing mechanism situated adjacent the assembling station for applying a sealing strip to the flanges of the axially alined can end and body, and actuating mechanism connected with and operating in timed relation said can end feed mechanism and said strip-applying mechanism.

21. In an apparatus for the described purpose, the combination with feed mechanisms for delivering a lined flanged can end and a flanged can body to an initial assembling station in axial alinement, of a support situated at said station for receiving and holding the can body separated from the can end, and a guide plate arranged above the said support and beneath which the can body is moved as delivered to said support.

22. In an apparatus for the described purpose, the combination with feed mechanisms for delivering a lined flanged can end and a flanged can body to an initial assembling 5 station in axial alinement, of means adjacent said assembling station for applying and compressing a sealing strip around the flanges of the assembled can end and body circumferentially thereof, a support situated 10 at said station for receiving and holding the can body separated from the can end, and mechanism operated by the can end or can body for controlling the means for feeding the can ends and can bodies to said station 15 in accordance as to whether there is a lined can end for assembling with a can body or a can body for assembling with a lined can end.
23. In an apparatus for the described 20 purpose, the combination with means for positioning a lined flanged can end and a flanged can body in spaced axial alinement at an initial assembling station, means for advancing the alined members in unison relative to an assembling station, and sealing 25 means adjacent said station for applying a sealing strip circumferentially of the flanges of the alined can end and body.
24. In an organized apparatus for the described purpose, the combination with interconnected means for placing a lined flanged can end and a flanged can body in axial alinement at an assembling station with the can body superposed relative to the can end, 30 means at said station for holding the can body to the can ends, and sealing mechanism adjacent the assembling station for applying to the flanges of the can end and can body a sealing strip for the hermetic sealing 35 thereof.
25. In an organized apparatus for the described purpose, the combination with interconnected means for placing a lined flanged can end and a flanged can body in spaced 40 axial alinement at an assembling station, means for advancing the alined parts to a seaming station with the can body superposed relative to the can end, means at said seaming station for holding the can body 45 to the can ends, sealing mechanism adjacent the assembling station for applying to the flanges of the can end and can body a sealing strip for the hermetic sealing thereof, means for feeding a sealing strip to said 50 sealing mechanism, devices for releasing said holding means from the held can on the completion of the sealing operation, and means for ejecting the released sealed can body.
26. In an apparatus for the described purpose, the combination with mechanism for delivering a lined flanged can end and a flanged can body in axial alinement relative to an assembling station with the can 55 body in superposed relation relative to the can end, a rotatable support situated at said station for receiving the axially alined members, a gage device for limiting the position of said members relative to the said support, rotatable means for clamping the can body 70 and end to the support, sealing mechanism for applying a sealing strip to the flanges of the can end and body for uniting the same hermetically, and means for ejecting the sealed can on the release thereof by the rotatable clamping means.
27. In an apparatus for the described purpose, the combination with feed mechanisms for delivering lined flanged can ends and flanged can bodies in spaced axial alinement 75 to an assembling station, means for supporting the can body spaced above the can end, and means associated therewith for controlling the action of said mechanisms in accordance as to whether there is a lined can end for feeding for assembling or a can body for placing in axial alinement with a lined can end.
28. In an apparatus for the described purpose, the combination with feed mechanisms 80 for delivering lined flanged can ends and flanged can bodies in spaced axial alinement to an assembling station, means associated therewith for controlling the action of said mechanisms in accordance as to whether there is a lined can end for feeding for assembling or a can body for placing in axial alinement with a lined can end.
29. In an apparatus for the described purpose, the combination with feed mechanisms 85 for delivering lined flanged can ends and flanged can bodies in spaced axial alinement to an assembling station, means associated therewith for controlling the action of said mechanisms in accordance as to whether there is a lined can end for feeding for assembling or a can body for placing in axial alinement with a lined can end, sealing mechanism situated adjacent the assembling 90 station for applying a sealing strip to the flanges of the alined end and body, and an ejector for removing the sealed can body on the completion of the sealing operation.
30. In an apparatus for the described purpose, the combination with feed mechanisms 95 for delivering lined flanged can ends and flanged can bodies in spaced axial alinement to an assembling station, means associated therewith for controlling the action of said mechanisms in accordance as to whether there is a lined can end for feeding for assembling or a can body for placing in axial alinement with a lined can end, sealing mechanism situated adjacent the assembling station for applying a sealing strip to the flanges of the alined end and body, an ejector for removing the sealed can body on the completion of the sealing operation, and means for feeding sealing strips to the sealing mechanism.
31. In an apparatus for the described purpose, the combination with feed mechanisms 100 for delivering lined flanged can ends and flanged can bodies in spaced axial alinement to an assembling station, means associated therewith for controlling the action of said mechanisms in accordance as to whether there is a lined can end for feeding for assembling or a can body for placing in axial alinement with a lined can end, sealing mechanism situated adjacent the assembling station for applying a sealing strip to the flanges of the alined end and body, an ejector for removing the sealed can body on the completion of the sealing operation, and means for feeding sealing strips to the sealing mechanism.
32. In an apparatus for the described purpose, the combination with feed mechanisms 105 for delivering lined flanged can ends and flanged can bodies in spaced axial alinement to an assembling station, means associated therewith for controlling the action of said mechanisms in accordance as to whether there is a lined can end for feeding for assembling or a can body for placing in axial alinement with a lined can end, sealing mechanism situated adjacent the assembling station for applying a sealing strip to the flanges of the alined end and body, an ejector for removing the sealed can body on the completion of the sealing operation, and means for feeding sealing strips to the sealing mechanism.
33. In an apparatus for the described purpose, the combination with feed mechanisms 110 for delivering lined flanged can ends and flanged can bodies in spaced axial alinement to an assembling station, means associated therewith for controlling the action of said mechanisms in accordance as to whether there is a lined can end for feeding for assembling or a can body for placing in axial alinement with a lined can end, sealing mechanism situated adjacent the assembling station for applying a sealing strip to the flanges of the alined end and body, an ejector for removing the sealed can body on the completion of the sealing operation, and means for feeding sealing strips to the sealing mechanism.
34. In an apparatus for the described purpose, the combination with feed mechanisms 115 for delivering lined flanged can ends and flanged can bodies in spaced axial alinement to an assembling station, means associated therewith for controlling the action of said mechanisms in accordance as to whether there is a lined can end for feeding for assembling or a can body for placing in axial alinement with a lined can end, sealing mechanism situated adjacent the assembling station for applying a sealing strip to the flanges of the alined end and body, an ejector for removing the sealed can body on the completion of the sealing operation, and means for feeding sealing strips to the sealing mechanism.
35. In an apparatus for the described purpose, the combination with feed mechanisms 120 for delivering lined flanged can ends and flanged can bodies in spaced axial alinement to an assembling station, means associated therewith for controlling the action of said mechanisms in accordance as to whether there is a lined can end for feeding for assembling or a can body for placing in axial alinement with a lined can end, sealing mechanism situated adjacent the assembling station for applying a sealing strip to the flanges of the alined end and body, an ejector for removing the sealed can body on the completion of the sealing operation, and means for feeding sealing strips to the sealing mechanism.
36. In an apparatus for the described purpose, the combination with feed mechanisms 125 for delivering lined flanged can ends and flanged can bodies in spaced axial alinement to an assembling station, means associated therewith for controlling the action of said mechanisms in accordance as to whether there is a lined can end for feeding for assembling or a can body for placing in axial alinement with a lined can end, sealing mechanism situated adjacent the assembling station for applying a sealing strip to the flanges of the alined end and body, an ejector for removing the sealed can body on the completion of the sealing operation, and means for feeding sealing strips to the sealing mechanism.
37. In an apparatus for the described purpose, the combination with feed mechanisms 130 for delivering lined flanged can ends and flanged can bodies in spaced axial alinement to an assembling station, means associated therewith for controlling the action of said mechanisms in accordance as to whether there is a lined can end for feeding for assembling or a can body for placing in axial alinement with a lined can end, sealing mechanism situated adjacent the assembling station for applying a sealing strip to the flanges of the alined end and body, an ejector for removing the sealed can body on the completion of the sealing operation, and means for feeding sealing strips to the sealing mechanism.

plying a sealing strip to the flanges of the alined end and body, an ejector for removing the sealed can body on the completion of the sealing operation, a knife or cutter 5 for severing the sealing strip at predetermined moments, and means controlled by the movement of the can end feed mechanism for actuating said knife.

31. In an organized apparatus for the described purpose, the combination with means for cutting and applying a ring liner to a flanged can end, can end feed mechanism for transferring said lined can end to an assembling station, feed means for placing 15 a can body in axial alinement with said end and in superposed relation therewith as advanced toward the assembling station, and sealing mechanism adjacent said station for applying a sealing strip to the flanges of 20 the said assembled can end and body for formation of a hermetic joint union.

32. In an organized apparatus for the described purpose, the combination with means for cutting and applying a ring liner to a flanged can end, can end feed mechanism for transferring said lined can end to an assembling station, feed means for placing 25 a can body in axial alinement with said end and in superposed relation therewith as advanced toward the assembling station, sealing mechanism adjacent said station for applying a sealing strip to the flanges of the said assembled can end and body for formation of a hermetic joint union, devices for 30 feeding a sealing strip to said mechanism, means for severing said strip at proper intervals, and means for ejecting the sealed can body on the completion of the sealing operation.

33. In an apparatus for the described purpose, the combination with means for positioning a lined flanged can end and a can body in axial alinement at an assembling station with the can body in superposed relation to the can end, mechanism adjacent 45 said station for applying a sealing strip to the flanges of the alined can end and body for the hermetic sealing thereof, and means for ejecting the sealed can body 50 on the completion of the sealing operation.

34. In an organized apparatus for the described purpose, the same comprising means for applying a ring liner to the flange of a can end, can end feed mechanism for transferring the lined can end to an initial assembling station and thence to an assembling station, mechanism operated in timed relation with the can end feed mechanism for feeding a can body to the initial assembling station 60 and in axial alinement with the lined can end, supporting means at said station for maintaining the axially alined can body separated from the can end, means carried by the can end feed mechanism for advancing the can body in unison with the

can end as transferred to the assembling station, rotatable devices at said station for receiving and holding the can end and body in clamped relation, sealing mechanism adjacent said station for applying and 70 compressing a sealing strip relative to the flanges of the can end and body, and means for ejecting the can body on the completion of the sealing operation.

35. In an apparatus for the described 75 purpose, provided with an assembling station, of mechanisms for assembling a ring liner and a can end and delivering a lined flanged can end and a flanged can body in axial alinement to said assembling station 80 with the can body in superposed relation relative to the can end.

36. An organized apparatus for the described purpose, the same comprising means for placing a gasket liner and a can end in 85 axial alinement, devices for applying the lining to the flange of the can end, co-acting means for advancing the said end and a can body into axial alinement, means for assembling said members and devices for 90 hermetically seaming the can end to the can body, and combined in said apparatus a power mechanism for actuating all of said instrumentalities in timed relation.

37. In an apparatus for the described 95 purpose, the combination with mechanism for delivering a lined flanged can end and a flanged can body in axial alinement to an assembling station with the can body superposed relative to the can end, devices for 100 clamping the can body to the can end, and means for compressing a sealing strip to the flanges of the can end and body for the hermetic sealing thereof.

38. In an apparatus for the described 105 purpose provided with an assembling station, the combination with supporting means situated at said station for receiving can ends and bodies, with the can bodies superposed relative to the can ends, mechanism for delivering to said support a lined flanged can end and a flanged can body in axial alinement with the can body in superposed relation relative to the can end, a member coöperating with said support for 110 the clamping of the alined can body and end thereto, and sealing means for compressing a sealing strip to the flanges of the held can end and body for the hermetic sealing 115 thereof.

39. In an apparatus for the described purpose provided with an assembling station, the combination with supporting means situated at said station for receiving can ends and bodies, mechanism for delivering 120 to said support a lined flanged can end and a flanged can body in axial alinement with the can body in superposed relation relative to the can end, a member coöperating with said support for the clamping of the alined 125

can body and end thereto, sealing means for compressing a sealing strip to the flanges of the held can end and body for the hermetic sealing thereof, devices for feeding 5 sealing strips to said sealing means, and means for releasing said clamping member from the can body after the completion of the sealing operation.

40. In an apparatus for the described purpose provided with an assembling station, the combination with supporting means situated at said station for receiving can ends and bodies, mechanism for delivering to said support a lined flanged can end 10 and a flanged can body in axial alinement with the can body in superposed relation relative to the can end, a member co-operating with said support for the clamping of the alined can body and ends thereto, sealing means for compressing a sealing strip 15 to the flanges of the held can end and body for the hermetic sealing thereof, devices for feeding sealing strips to said sealing means, means for releasing said clamping member from the can body after the completion 20 of the sealing operation, and devices for ejecting the released can body.

41. In an apparatus for the described purpose, the combination with the sealing mechanism thereof, of means for lining a flanged can end and means for delivering within the sphere of said mechanism a lined flanged can end and a flanged can body in axial alinement therewith and superposed relative 30 to the said end.

42. In an apparatus for the described purpose, the combination with mechanism for feeding a lined flanged can end and flanged can body to an assembling station in axial alinement, and means associated therewith 40 for controlling the feed of can bodies in accordance as to whether a lined can end is positioned for feeding to said assembling station, and means at said station for applying 45 a sealing strip to the flanges of an alined can end and body.

43. In an apparatus for the described purpose, the combination with mechanism for feeding lined flanged can ends and flanged can bodies to an assembling station in axial alinement, of means associated therewith 50 for controlling the feed of the can ends in accordance as to whether a flanged can body is positioned for feeding toward the assembling station, and means at said station for applying a sealing strip to the flanges of an alined can end and body.

44. In an apparatus for the described purpose, the combination with reciprocating 60 mechanism for feeding lined flanged can ends to an initial assembling station and subsequently transferring the same to an assembling station, of reciprocating feed mechanism actuated in timed relation with the 65 can end feed mechanism and adapted to de-

liver a flanged can body to the initial assembling station in axial alinement with the lined can end and in superposed relation therewith, of means carried by the can end feed mechanism for engaging with a positioned can body and moving the same to the assembling station in unison with the lined can end, and mechanism situated at said station for compressing a sealing strip relative to the flanges of the can end and body for 70 the formation of a hermetic seal.

45. In an apparatus for the described purpose, the combination with the feed mechanism for delivering lined can ends and the feed mechanism for delivering flanged can bodies in axial alinement therewith, and means for supporting the can bodies spaced above the can ends, of means for controlling the action of said mechanisms in accordance as to whether there is a lined can end or a 80 flanged can body positioned for feeding to an assembling station.

46. In a machine wherein a gasket liner is assembled with a can end by superposition thereon, and having means for that purpose, 90 the combination therewith of means for superposing a flanged can body on said assembled gasket and can end.

47. In an apparatus for the described purpose, the combination with feed mechanism 95 for lined flanged can ends, of mechanism for delivering flanged can bodies in axial alinement with said ends and in superposed relation thereto, and mechanism for controlling the operation of said mechanisms in accordance as to whether there is a lined can end or a flanged can body in position for feeding. 100

48. In an apparatus for the described purpose, the combination with a rotatable carrying member for placing a lined flanged can end in feeding position, of feed mechanism for moving said lined can end to an assembling station, means for feeding a flanged can body to said station in axial alinement with said end and in superposed 105 relation thereto, devices for controlling the feed of the can ends in accordance as to whether a can body is positioned for feeding relative to the can end, and devices for ejecting the lined can end from the carrying 110 member in the absence of a can body for feeding relative to the can end.

49. In an apparatus for the described purpose, the combination with a rotatable carrying member for placing a lined flanged can end in feeding position, of feed mechanism for moving said lined can end to an assembling station, means for feeding a flanged can body to said station in axial alinement with said end and in superposed 115 relation thereto, devices for controlling the feed of the can ends in accordance as to whether a can body is positioned for feeding relative to the can end, devices for ejecting the lined can end from the carrying 120 member.

ber in the absence of a can body for feeding relative to the can end, and mechanism situated at the assembling station for compressing a sealing strip relative to the flanges of the axial alined can end and body.

50. In an apparatus for the described purpose, the combination with a rotatable carrying member for placing a lined flanged can end in feeding position, of feed mechanism for moving said lined can end to an assembling station, means for feeding a flanged can body to said station in axial alinement with said end and in superposed relation thereto, devices for controlling the feed of the can ends in accordance as to whether a can body is positioned for feeding relative to the can end, devices for ejecting the lined can end from the carrying member in the absence of a can body for feeding relative to the can end, means for clamping the can body to the can end, and mechanism situated at the assembling station for compressing a sealing strip relative to the flanges of the axial alined can end and body.

51. An organized apparatus for the described purpose, the same comprising automatically operated feeding means for delivering and positioning a gasket lined flanged can end and a flanged can body in axial alinement with the can body superposed relative to the can end, means whereby the said body is held spaced from the can end, means for conveying the alined members to assembling position while gradually placing the can body in contact with the can end, and sealing mechanism situated at said station for compressing a sealing strip relative to the flanges of the can end and body

40 for the formation of a hermetic seal.

52. An organized apparatus for the described purpose, the same comprising automatically operated feeding means for delivering and positioning a gasket lined flanged can end and a flanged can body in axial alinement with the can body superposed relative to the can end and held spaced therefrom and conveying the alined members to assembling position while gradually placing the can body in contact with the can end, rotatable means for receiving and supporting the said members, devices for clamping the can body to the end and holding the same so clamped during a sealing operation, sealing mechanism situated at said station for compressing a sealing strip relative to the flanges of the can end and body for the formation of a hermetic seal, means for feeding a sealing strip to said sealing mechanism, devices for releasing the clamping can body, and means for ejecting the sealed can body on the completion of the sealing operation.

53. An organized apparatus for the described purpose, the same comprising auto-

matically operated feeding means for delivering and positioning a gasket lined flanged can end and a flanged can body in axial alinement with the can body superposed relative to the can end, means whereby the 70 said body is held spaced from the can end, means for conveying the alined members to assembling position while gradually placing the can body in contact with the can end, devices controlling the operation of the 75 feeding means in accordance as to whether there is a lined can end or a can body positioned for placing in axial alinement one with the other, and sealing mechanism situated at said station for compressing a sealing strip relative to the flanges of the can end and body for the formation of a hermetic seal.

54. An organized apparatus for the described purpose, the same comprising reciprocating feed mechanism for delivering a lined flanged can end to an initial assembling station and thence transferring the same to an assembling station, horizontally reciprocating feed mechanism working in 85 timed relation with the can end feed mechanism for delivering a flanged can body to the initial assembling station and in axial alinement with the lined can end and in superposed relation therewith, means at said 95 station for supporting the can body spaced from the can end, means carried by the can end feed mechanism for advancing the can body to the assembling station in unison with the can end, and sealing mechanism 100 situated at the assembling station for compressing a sealing strip relative to the flange of the can end and body for the formation of a hermetic seal.

55. An organized apparatus for the described purpose, the same comprising reciprocating feed mechanism for delivering a lined flanged can end to an initial assembling station and thence transferring the same to an assembling station, horizontally reciprocating feed mechanism working in 110 timed relation with the can end feed mechanism for delivering a flanged can body to the initial assembling station and in axial alinement with the lined can end and in superposed relation therewith, means at said 115 station for supporting the can body spaced from the can end, associated instrumentalities for controlling the operation of the said feed mechanisms in accordance as to 120 whether there is a lined can end or a flanged can body for feeding to the initial assembling station, means carried by the can end feed mechanism for advancing the can body to the assembling station in unison with the 125 can end, and sealing mechanism situated at the assembling station for compressing a sealing strip relative to the flange of the can end and body for the formation of a hermetic seal.

56. An organized apparatus for the described purpose, the same comprising reciprocating feed mechanism for delivering a lined flanged can end to an initial assembling station and thence transferring the same to an assembling station, horizontally reciprocating feed mechanism working in timed relation with the can end feed mechanism for delivering a flanged can body to the initial assembling station and in axial alinement with the lined can end and in superposed relation therewith, means at said station for supporting the can body spaced from the can end, associated instrumentalities for controlling the operation of the said feed mechanisms in accordance as to whether there is a lined can end or a flanged can body for feeding to the initial assembling station, means carried by the can end feed mechanism for advancing the can body to the assembling station in unison with the can end, a rotatable support at the assembling station for receiving the alined can end and body, a rotatable device for clamping the can body and end to said support and holding the same so clamped during a sealing operation, and sealing mechanism situated at the assembling station for compressing a sealing strip relative to the flange of the can end and body for the formation of a hermetic seal.

57. An organized automatic apparatus for the described purpose, the same comprising interconnected feed mechanism operated in timed relation for delivering a lined flanged can end and a flanged can body in axial alinement to an assembling station with the can body in superposed relation relative to the can end, means for holding the can body clamped to the can end during a sealing operation, and mechanism for applying a sealing strip to the flanges of the can end and body for the formation of a hermetic seal.

58. In an apparatus for the described purpose, the combination with sealing mechanism for compressing a sealing strip to the flanges of an assembled lined can end and can body for the formation of a hermetic seal, of associated means for placing a lined flanged end and a flanged can body in axial alinement within the sphere of the sealing mechanism with the can body in superposed relation relative to the can end.

59. In an apparatus for the described purpose, the combination with sealing mechanism for compressing a sealing strip to the flanges of an assembled lined can end and can body for the formation of a hermetic seal, of associated means for placing a lined flanged end and a flanged can body in axial alinement within the sphere of the sealing mechanism with the can body in superposed relation relative to the can end,

and devices for holding the can body clamped to the can end during the sealing operation.

60. In an apparatus for the described purpose, the combination with means for depositing a lined flanged can end and a flanged can body in axial alinement at an initial assembling station with the can body in superposed relation relative to the can end, devices for advancing said alined members in unison to an assembling station, rotatable means for holding the can body clamped to the can end at said station, and sealing mechanism for imparting rotation to the clamped members while compressing a sealing strip to the flanges thereof for the formation of a hermetic seal.

61. In an apparatus for the described purpose, the combination with reciprocating feed slides for assembling a lined flanged can end and a flanged can body in axial alinement with the can body in superposed relation relative to the can end, rack controlled means for actuating said slides in timed relation, and devices for controlling the action of said rack controlled means for controlling the action of the feed slides in accordance as to whether there is positioned a lined can end or a can body for feeding for assembling relative to each other.

62. In an apparatus for the described purpose, the combination with reciprocating feed slides for assembling a lined flanged can end and a flanged can body in axial alinement with the can body in superposed relation relative to the can end, rack controlled means for actuating said slides in timed relation, devices operated by the can end or can body for controlling the action of said rack controlled means for actuating the feed slides in accordance as to whether there is either a lined can end or a can body in position for feeding for assembling relative to each other, means moved with the can end feed slide for transferring the can body in unison with the can end to an assembling station, and sealing mechanism at the assembling station for applying a sealing strip to the flanges of the assembled can end and can body.

63. In a machine for the described purpose, the combination with a support situated at an assembling station for receiving a lined flanged can end and a flanged can body in axial alinement, mechanism for delivering a can end and body onto said support separately and in axial alinement, means for gaging the position of said members relative to the said support, and sealing mechanism for compressing a sealing strip relative to the flanges of the assembled can end and body.

64. In a machine for the described pur-

- pose, the combination with a support situated at an assembling station for receiving a lined flanged can end and a flanged can body in axial alinement, mechanism for delivering a can end and body onto said support separately and in axial alinement, means for gaging the position of said members relative to the said support, sealing mechanism for compressing a sealing strip relative to the flanges of the assembled can end and body, and means for automatically ejecting the can body on the completion of the sealing operation.
65. In a machine for the described purpose, the combination with a support situated at an assembling station for receiving a lined flanged can end and a flanged can body in axial alinement, mechanism for delivering a can end and body onto said support separately and in axial alinement, means for gaging the position of said members relative to the said support, devices for clamping the can end and body to said support, and sealing mechanism for compressing a sealing strip relative to the flanges of the assembled can end and body.
66. In a machine for the described purpose, the combination with a freely rotatable support situated at an assembling station for receiving a lined flanged can end and a flanged can body separately and in axial alinement, mechanism for delivering a can end and body onto said support separately and in axial alinement, means for gaging the position of said members relative to the said support, rotatable means for clamping the can body and end to said support, devices for releasing the clamped can and end on the completion of a sealing operation, and sealing mechanism for imparting rotation to the clamped body and end and applying to and compressing a sealing strip relative to the flanges of the assembled can end and body.
67. An organized apparatus for the described purpose, the same comprising means for placing a gasket lined flanged can end and a flanged can body separately and in axial alined position with the can body uppermost and held separated from the can end, devices for conveying the axially alined can body and end to assembled position onto a horizontally disposed support, means for clamping the can body to the can end and holding the same so clamped during a sealing operation, and sealing mechanism for compressing a sealing strip relative to the flanges of the clamped end and body for the formation of a hermetic seal.
68. An apparatus for the described purpose, the same comprising reciprocating feed mechanism for delivering a lined flanged can end to an initial assembling station and at a subsequent movement thereof transferring the same to an assembling station, recipro-
- cating mechanism coöperating in timed relation therewith for placing a flanged can body at the initial assembling station and in axial alinement with the can end, means for transferring the can body in unison with the can end from the initial assembling station to the assembling station, clamping means for holding the can body to the can end at said station during a sealing operation, sealing mechanism for applying a sealing strip to the flanges of the clamped can end and body for the formation of a hermetic seal, and devices for ejecting the can body with the end sealed thereto on the completion of the sealing operation.
69. An apparatus for the described purpose, the same comprising reciprocating feed mechanism for delivering a lined flanged can end to an initial assembling station and at a subsequent movement thereof transferring the same to an assembling station, reciprocating mechanism coöperating in timed relation therewith for placing a flanged can body at the initial assembling station and in axial alinement with the can end, means for transferring the can body in unison with the can end from the initial assembling station to the assembling station, clamping means for holding the can body to the can end at said station during a sealing operation, sealing mechanism for applying a sealing strip to the flanges of the clamped can end and body for the formation of a hermetic seal, and devices for ejecting the can body with the end sealed thereto on the completion of the sealing operation.
70. An apparatus for the described purpose, the same consisting of the combination of interconnected working and timed instrumentalities for receiving and automatically placing flanged can ends and flanged can bodies in spaced axial alinement at an initial assembling station with the can body superposed relative to the can end and transferring the said alined members to an assembling station, means interposed within the path of travel of the alined members for causing the can body to move gradually into contact with the can end during such transfer movement, means for clamping the can body down upon the can end, and mechanism for applying a removable sealing strip to the flanges of the assembled and clamped can end and body circumferentially thereof for the forming of a hermetic seal-union therebetween.
71. In an apparatus for the described purpose, the combination with a reciprocating feed slide for receiving and moving a lined flanged can end on one stroke thereof to an

initial assembling station and on a subsequent stroke transferring the same to an assembling station, means associated therewith for holding the lined can end at the 5 initial assembling station on the return stroke of said feed slide, a reciprocating slide for positioning a flanged can body at the initial assembling station in axial alinement with the can end and in superposed relation thereto, and a support at said station for receiving the can body and holding the same separated from the can end.

72. In an apparatus for the described purpose, the combination with a reciprocating 15 feed slide for receiving and moving a lined flanged can end on one stroke thereof to an initial assembling station and on a subsequent stroke transferring the same to an assembling station, means associated therewith for holding the lined can end at the 20 initial assembling station on the return stroke of said feed slide, a reciprocating slide for positioning a flanged can body at the initial assembling station in axial alinement with the can end and in superposed relation thereto, a support at said station for receiving the can body and holding the same separated from the can end, a guide plate situated at the said station beneath 25 which the can body moves and by means of which it is held to the support therefor, and means for moving the can body in unison with the can end on its transfer to the assembling station.

30 73. In an apparatus for the described purpose, the combination with a reciprocating feed slide for receiving and moving a lined flanged can end on one stroke thereof to an initial assembling station and on a subsequent 35 stroke transferring the same to an assembling station, means associated therewith for holding the lined can end at the initial assembling station on the return stroke of said feed slide, a reciprocating slide for positioning a flanged can body at the initial assembling station in axial alinement with the can end and in superposed relation thereto, a support at said station for receiving the can body and holding the same 40 separated from the can end, a guide plate situated at the said station beneath which the can body moves and by means of which it is held to the support therefor, means for moving the can body in unison with the can end on its transfer to the assembling station, and means controlling the operation of the can end feed mechanism and the can body feed mechanism in accordance as to whether there is positioned a lined can end or a can 45 body for feeding to the initial assembling station.

60 74. In an apparatus for the described purpose, the combination with interconnected reciprocating instrumentalities operated in 65 timed relation for successively delivering

lined flanged can ends and flanged can bodies in axial alinement to an assembling station with the can body in superposed relation to the can end, and means carried by one of said instrumentalities for transferring an alined can body in unison with a can end to an assembling station. 70

75. In an apparatus for the described purpose, the combination with interconnected reciprocating instrumentalities operated in 75 timed relation for successively delivering lined flanged can ends and flanged can bodies in axial alinement to an assembling station with the can body in superposed relation to the can end, means carried by one of said instrumentalities for transferring an alined can body in unison with a can end to an assembling station, and sealing mechanism situated at said station for compressing a sealing strip relative to the flanges of the 80 can end and body for the formation of a hermetic seal. 85

76. In an apparatus for the described purpose, the combination with interconnected reciprocating instrumentalities operated in 90 timed relation for successively delivering lined flanged can ends and flanged can bodies in axial alinement to an assembling station with the can body in superposed relation to the can end, means carried by one of said 95 instrumentalities for transferring an alined can body in unison with a can end to an assembling station, means for holding the can body clamped to the can end during a sealing operation, and sealing mechanism 100 situated at said station for compressing a sealing strip relative to the flanges of the can end and body for the formation of a hermetic seal.

77. In an apparatus for the described purpose, the combination with means for positioning a line flanged can end for delivery to an initial assembling station, of a reciprocating feed slide for moving said can end to the initial assembling station and at a subsequent period of its movement transferring the same to an assembling station, an endless carrier for successively positioning flanged can bodies for feeding to the initial assembling station, a reciprocating feed slide for 110 successively transferring the said can bodies from the endless carrier to the initial assembling station and in axial alinement with the can end, means carried by the can end feed slide for transferring the alined can 115 body in unison with its can end to an assembling station, and sealing mechanism for compressing a sealing strip relative to the flanges of the assembled can end and body. 120

78. In an apparatus for the described purpose, the combination with a spring held rotatable plunger for clamping at the assembling station of the apparatus an axially alined flanged can body to a lined flange can end, of a rotatable support to which said 125 130

- members are held clamped, a pair of vertically disposed sealing rollers for applying and compressing a sealing strip to the flange of a can end and body clamped to the 5 table support, the upper roller of the pair being mounted for vertical swinging movement, and connection between the upper roller of the pair and the spring held plunger for raising the same with the release of 10 the clamped can body on the completion of the seaming operation.
79. In an apparatus for the described purpose, the combination with a rotatable support, of mechanisms for delivering a lined 15 flanged can end and a flanged can body onto said support in axial alinement with the can body in superposed relation relative to the can end, a cam actuated spring held plunger co-acting with said support for holding the can 20 end and body clamped thereto, a pair of vertically disposed seaming rollers for compressing a sealing strip to the flanges of the clamped can end and body, the upper roller being hinged for vertical movement, con- 25 nection between said roller and the spring held plunger for raising the same on the release of the plunger on the completion of the sealing operation, and means for ejecting the sealed can body from the rotatable sup- 30 port.
80. In an apparatus for the described purpose, the combination with a support situated at the assembling station of the apparatus, of mechanism for delivering a lined 35 flanged can end and a flanged can body in axial alinement to said support with the can body in superposed relation to the can end, a swinging gage for positioning the can end and body relative to said support, vertically 40 movable means for clamping the can body and end to said support, sealing mechanism for applying a sealing strip to the flanges of the clamped can end and can body, and an ejector carried by the swinging gage for 45 ejecting the sealed can body on the completion of the sealing operation, and means acting in timed relation with the sealing mechanism for swinging the said gage and ejector device.
- 50 81. An apparatus for applying and sealing a gasket lined flanged can end to the bottom of a flanged can body, the same comprising means for placing a flanged can body in axial alinement with a lined flanged can end 55 and in superposed relation therewith, and sealing mechanism for applying a sealing strip to the flanges of the said alined end and can body for the formation of a hermetic seal.
- 60 82. An apparatus for applying and sealing a gasket lined flanged can end to the bottom of a flanged can body, the same comprising means for applying a gasket liner to a flanged can end, mechanism for transferring 65 said end to an assembling station, devices for delivering a flanged can body to said station in axial alinement with said can end and in superposed relation therewith, and sealing mechanism for applying a sealing strip to the flanges of the end and body for the 70 formation of a hermetic seal.
83. An organized apparatus for the described purpose, the same comprising associated instrumentalities for cutting a gasket ring liner and applying the same to the 75 flange of a can end and advancing the lined can end to feeding position, devices for transferring said lined end to an assembling station, interconnected means for positioning a flanged can body at said station in axial 80 alinement with the lined can end and in superposed relation therewith, devices for holding the can body to the can end, sealing mechanism for applying a sealing strip to the flanges of the can end and body for the 85 formation of a hermetic seal, and means for feeding a sealing strip to said mechanism.
84. In an organized apparatus, the combination with associated means for applying a gasket liner to the flange of a can end and 90 depositing the lined end at an assembling station, and means associated therewith for placing a flanged can body in axial alinement with the said can end and in superposed relation therewith, and sealing mecha- 95 nism for applying and compressing a sealing strip to the flanges of the said can end and body for the formation of a hermetic seal.
85. In an organized apparatus, the combination of intermittently operating mechanism for bringing a gasket lined flanged end and a flanged can body in axial alinement at an assembling station with the can body superposed relative to the can end, and sealing 100 mechanism for applying a sealing strip to the flanges of the can end and body for the formation of a hermetic seal.
86. In an organized apparatus, the combination of intermittently operating mechanism for bringing a gasket lined flanged end and a flanged can body in axial alinement to an assembling station with the can body superposed relative to the can end, devices for holding the alined members in 110 fixed relation during a sealing operation, and sealing mechanism for applying a sealing strip to the flanges of the can end and body for the formation of a hermetic seal.
87. In an apparatus for the described purpose, the combination with a freely rotatable support situated at an assembling station, of means for delivering a lined flanged can end and a flanged can body separately and in axial alinement with said support with the 115 can body in superposed relation to the can end, and a spring held cam actuated freely rotatable disk for clamping said alined end and body to said support.
88. In a machine wherein a gasket liner 120

is assembled with a can end by superposition thereon, and having means for that purpose, the combination therewith of means for superposing a flanged can body on said assembled gasket and can end and means for applying a sealing strip to embrace the flanges of said can end and can body and to compress between them said gasket liner.

89. In an apparatus for the described purpose, the combination with reciprocating slides for delivering a lined flanged can end and a flanged can body separately and in axial alinement to an initial assembling station with the can body superposed relative to the can end, rack controlled means for actuating said feed slides in timed relation, means for advancing the alined end and body to an assembling station and applying the can body to the can end, and sealing mechanism for compressing a sealing strip to the flanges of the can end and body.

90. In a machine for the described purpose, the combination with means for assembling a lined flanged can end and a flanged can body in axial alinement with the can body superposed relative to the can end, sealing mechanism for compressing a sealing strip to the flanges of the alined can end and body for formation of a hermetic seal, and means for ejecting the sealed can body.

91. In a machine for the described purpose, the combination with reciprocating feed slides for moving gasket lined flanged can ends and flanged can bodies into axial alinement with the can body superposed relative to the can end, each of said slides provided with a rack section, gears meshing with said portions, rack segments meshing with said gears, a rotatable shaft to which said rack segments are secured, a rock shaft for actuating said shaft, and spring controlled clutch actuated means operated by the can end or can body for controlling the movement of said shaft for regulating the movements of the feed slides in accordance as to whether a lined can end or a flanged can body is positioned for feeding for assembling purposes.

92. In a machine for the described purpose, the combination with reciprocating feed slides for moving gasket lined flanged can ends and flanged can bodies into axial alinement with the can body superposed relative to the can end, each of said slides provided with a rack section, gears meshing with said portions, rack segments meshing with said gears, a rotatable shaft to which said rack segments are secured, and means controlled by the can end or can body for imparting rotary movement to said shaft for actuating the feed slides in accordance as to whether a lined can end or a can body is positioned for feeding for assembling purposes.

93. An organized apparatus for the described purpose, the same comprising means for feeding and applying gasket liners to can ends, associated instrumentalities for placing the said end and a can body in spaced axial alinement, means for assembling the alined members, and mechanism for hermetically seaming the can end and the said body.

94. An organized apparatus for the described purpose, the same comprising means for cutting a gasket liner from liner material, and positioning and placing the said liner in axial alinement with the positioned can end, devices for applying the liner to the can end, associated instrumentalities for advancing the can end and a can body into spaced axial alinement, means for assembling the said can end and can body, and mechanism for hermetically seaming the can end to the can body.

95. In an apparatus of the character described, the combination of mechanism for placing a paper ring liner or gasket loosely upon the flange of a flanged can end, means coöperating with said mechanism for disposing the flange of a flanged can body upon the loose liner to retain it between the flanges of the can body and end, and means for seaming said flanges together.

96. In an apparatus adapted for operation upon liner material and separate can ends and can bodies, the combination of means for cutting a ring liner from suitable flat material, means for placing said liner loosely upon the flange of a can end, means coöperating with said placing means for transferring said liner and can end to a flanged can body, and means for seaming the can end to the can body.

97. In an apparatus adapted for operation upon separate ring liners and can ends and can bodies, the combination of means for feeding a cut ring liner, means for feeding a can end, means for feeding a flanged can body, said means coöperating to position the can end and can body in axial alinement at a seaming station with the liner loosely held between said flanges of said end and body and seaming means at the seaming station.

98. In an apparatus of the character described, the combination of means for forming a ring liner, means for positioning the ring liner upon the flange of a flanged can end, means coöperating with the liner forming and positioning means for positioning said end with said liner in proper relation with the flange of a flanged can body and means for seaming said flanges together with the liner between them.

99. In an apparatus of the character described, the combination of means for positioning the ring liner upon the flange of a flanged can end, means coöperating with

the liner positioning means for positioning said end with said liner in proper relation with the flange of a flanged can body, and means for seaming said flanges together with the liner between them.

100. In a machine of the character described, the combination of means for feeding and supporting a can body, a can head, and a ring liner, with means for placing the

latter on one of the former and means for 10 seaming all three together.

In testimony whereof I have signed my name to this specification in the presence of two subscribing witnesses.

IVAN D. THORNBURGH.
